UNITED STATES PATENT OFFICE.

WARREN D. HOUSE, OF KANSAS CITY, MISSOURI.

ELEVATOR-GUARD.

SPECIFICATION forming part of Letters Patent No. 391,615, dated October 23, 1888.

Application filed May 31, 1888. Serial No. 275,570. (No model.)

To all whom it may concern:

Be it known that I, WARREN D. HOUSE, a citizen of the United States, residing at Kansas City, in the county of Jackson and State of Missouri, have invented certain new and useful Improvements in Automatic Guards for Hatchway-Elevators; and I do hereby declare the following to be a full, clear, and exact description of the invention, such as will enable others skilled in the art to which it appertains to make and use the same.

My invention relates to certain new and useful improvements in automatic gates for hatchway-elevators, and particularly to features of construction, as hereinafter described, whereby the device may be readily and quickly adjusted in place when originally installed and said adjustment altered thereafter to correspond to changing conditions of wear.

In the accompanying drawings, illustrative of my invention, Figure 1 represents a side elevation of one form or modification of the same in position for use. Fig. 2 represents on a larger scale a like view, partly broken away, and showing the details of construction of the gate-operating mechanism. Fig. 3 represents an end elevation of the gate and its operating connections. Fig. 4 represents the same partly in section. Fig. 4^a represents in detail the adjustable connection between the gate and its operating-shaft. Fig. 5 represents a side elevation of a modification of my invention, and Fig. 6 represents an end view thereof.

Similar letters of reference indicate similar parts throughout the several views.

Referring to the figures upon Sheet 1 of the drawings, A indicates the cage or car of an elevator-hatchway, provided with suitable means for raising and lowering the same, said car being provided with a double cam-surface, a, projecting from one of its sides. Across the hatchway at each of the floor-landings thereof are located gates f, pivoted loosely upon a revoluble rock-shaft, x, which turns freely in a bearing, d, secured to a post, k, at one corner of the hatchway-opening. A catch, g, attached to an opposite post receives the free end of the gate when said gate is in a horizontal position, indicated in dotted lines in Fig. 1. The rock-shaft x is provided at one end with the crank-arms y integral therewith,

and upon which is mounted the loosely-turning friction-roller b, said friction-roller being located in the path of movement of the double cam-projection a. The opposite end of the rock-shaft, after passing through the opening in the gate, is of square or hexagonal cross-section, as represented, respectively, at m in Figs. 1 and 2 and in Fig. 4. Upon the squared or hexagonal portion is located the crank-arm c, held in place by a nut, n, or its equivalent, against longitudinal displacement. The said crank-arm has an aperture, s, corresponding in shape to the cross-section of the portion m of the rock-shaft, and is therefore locked thereon so as to turn with the rock-shaft. At its outer end the crank-arm c is connected with the gate f by means of a bolt, i, passing through both crank-arm and gate, as shown.

The construction described enables me to adjust the device in place with respect to a floor or landing of an elevator-shaft with convenience and expedition. To accomplish this I first erect the post k at one corner of the hatchway-opening and at a convenient height upon the inner face of said post attach the bearing d, having previously inserted the rock-shaft x in place, said rock-shaft being provided with its crank-arm y and roller b. The elevator-car is now raised until the roller b is just clear of the extreme end of the cam-surface a; the gate f is then placed upon the rock-shaft x and brought to a horizontal position, whereupon the crank-arm c is also placed on said shaft. A hole is then bored in the gate opposite the aperture t in the free end of the crank-arm and the bolt i is inserted, thereby locking the gate f to the rock-shaft x. The advantage of employing these connections is that without particular care as to the exact location or position of the post k or the cam a with relation thereto the gate can be, at the place of installment and without the exercise of particular skill on the part of the workmen, immediately and exactly connected to the leverage system, so as to assume the horizontal position at the exact point where the cam leaves the friction-roller in the upward and downward movements of the car A. Should the post k in the course of time be somewhat displaced by warping or the like, or should the cam be worn away materially, thereby failing to raise the gate to a sufficient height during the operation

of the device, this displacement may be compensated for by removing the crank-arm c from the rock-shaft x , and then replacing it at a different angle with respect thereto, bringing 5 the roller to the position above referred to, placing the gate in the horizontal position, as above, and then boring a new bolt-hole for the reception of the bolt i .

The general operation of the construction 10 will be apparent. Thus, when the car has passed any particular landing, the gate f is in the horizontal position, its free end resting in the catch g , and the friction-roller b is at the inner limit of its throw. When the car rises 15 or descends, as the case may be, the cam projection a comes in contact with the roller b , and the roller with its crank-arm y is thrown back gradually, thereby revolving the rock-shaft x , and with said rock-shaft the crank- 20 arm c . The crank-arm c , through the intermediacy of the bolt i , revolves the gate f until the latter is made to assume a vertical or nearly vertical position, thereby permitting entrance to and exit from the car at the moment 25 that said car is opposite the landing. Upon the upper edge of the gate f is located a spring, v , which is adapted to strike against a projection, w , upon the post k and be slightly compressed thereby when the gate f is at the upper 30 limit of its path of movement. When, now, the car proceeds to an upper or lower landing, as the case may be, the spring v , as soon as one of the cam-surfaces comes opposite the roller b , forces the gate f downward from 35 the vertical position and against said cam surface and thereafter the weight of the gate will cause it to descend, the roller being permitted by the oppositely - inclined surface of the double cam to resume gradually its original 40 position until, when the car has passed, the gate is once more in the horizontal plane and bars the hatchway.

When the hatchway is located in the center of a building and is accessible from opposite 45 sides, it is evident that two gates will be employed for each landing. In this event I provide each of the said gates with a rock-shaft, x , crank-arm c , and bolt i . It is not necessary, however, that each should be provided with 50 the roller b , or that there should be two cams, a , operating together. To obviate this necessity I connect the opposite rock-shafts x by means of a rod, w , entering openings in projections v at the inner ends of the rock-shafts 55 x and being locked in said openings against rotation.

In the form of my invention illustrated in Figs. 5 and 6 the gate f' is connected with a shaft, x' , by a crank-arm, c' , and bolt i' in a similar manner to that hereinbefore described with reference to the preceding figures of the drawings. The rock-shaft x' , however, in this case is located at the rear of the post k' , and the roller b' is mounted upon an arm, z , connected

with a shaft, l , mounted in suitable bearings 65 upon the front face of the post k' . A link, p , connects the arm z with a crank-arm, y' , upon the rock-shaft x' , said crank-arm y' being shorter than the crank-arm z , whereby any rocking movement of the shaft l will be multiplied in its transmission to the rock-shaft x' . This arrangement of parts I employ when, from 70 particular conditions of use, it is impracticable to impart too great a movement of oscillation to the roller b . With this construction it 75 is obvious that it is not necessary for the crank-arm z to project at so great an angle with respect to the car A' , and therefore the shock of impact of the cam a' upon the roller b' is less 80 than in the structure shown on Sheet 1. Moreover, the gate f' , when in its vertical position, does not project over the entrance to the car, and persons may therefore enter and pass out of the car without liability of striking against 85 the gate.

In Fig. 6 I have illustrated with respect to the modified form of my invention the means hereinbefore described for simultaneously operating opposite gates of a centrally-located hatchway by means of a single cam-surface, 90 the operating-shafts of said gates in this instance being connected, as before described, through the intermediacy of the rod w' .

Having thus described my invention, what I claim, and desire to secure by Letters Patent, 95 is—

1. The combination, with an elevator-car provided with a double cam-surface upon one of its sides, of a roller located in the path of movement of said double cam-surface, a crank-arm upon which said roller is mounted, a rock-shaft connected with said crank-arm, a hatchway-gate having an aperture through which said rock-shaft passes freely, a crank-arm fitting over said rock-shaft beyond the gate and locked against rotation thereon, and a bolt for securing the lower end of said crank-arm to the hatchway-gate, substantially as described. 100

2. The combination, with an elevator-car provided with a double cam-surface upon one of its sides, of a roller located in the path of movement of said double cam-surface, a crank-arm upon which said roller is mounted, a rock-shaft having a shorter crank-arm than that upon which the roller is mounted, a link connecting said crank-arms, a hatchway-gate having an aperture through which said rock-shaft passes freely, a crank-arm fitted over said rock-shaft beyond the gate and locked against rotation thereon, and a bolt for securing the lower end of said crank-arm to the hatchway-gate, substantially as described. 115

In testimony whereof I affix my signature in presence of two witnessss.
